UNITED STATES PATENT OFFICE.

JOHN T. PHIPPS AND HERMAN C. SMITH, OF WHITTIER, CALIFORNIA; SAID PHIPPS
ASSIGNOR TO SAID SMITH.

CORE DRILL.

Application filed November 17, 1924. Serial No. 750,305.

Our present invention is a core drill; and it is an especial object of this invention to provide a core drill utilizing the well known advantages of a disc bit.

It is a further object of this invention to provide a core drill having ample and efficient means for the delivery of a circulating fluid to the cutting discs, or the like.

It is a further object of this invention to provide a drill comprising a toothed annulus 10 efficiently co-operating with a pair of rotatable discs in the cutting of a core.

It is a further object of this invention to provide a drill bit comprising a pair of disc cutters supported from a hollow body by a tubular neck; and it is an especial object of this invention to use said tubular neck in the support of an annular cutter, or in the support of a core barrel, or in the support of both 20 of the last mentioned elements in substantial alignment.

It is a further object of this invention to provide a disc drill comprising a hollow body threaded at its upper end for connection with 25 a drill pipe, or the like, and provided also with means for so supporting a core barrel that the latter may extend into said drill pipe, said body being preferably sectional and provided with a central bore of sufficient diameter to 30 permit the downward movement of a circulating fluid past said barrel and toward openings, which may be below the lower end thereof.

It is a further object of this invention to 35 provide a core bit comprising cutting discs and a toothed annular cutter, said annular cutter terminating in substantially the same horizontal plane or in a lower plane than said discs, and being preferably so constructed as 40 to throw its chips toward the path of said discs.

It is a further object of this invention to 45 provide improved means, which may include hardened nuts serving also as bearings, for the rotatable support and removable retention of cutting discs upon a drill body.

Other objects of our invention will appear from the following description of an advantageous embodiment thereof taken in connection with the appended claims and the accompanying drawings, in which

Fig. 1 is a vertical longitudinal section.

Fig. 2 is a bottom plan view.

Fig. 3 is a cross section on the line 3—3 of 55 Fig. 1.

Fig. 4 is a cross section on the line 4—4 of Fig. 1.

Fig. 5 is a fragmentary view taken substantially as indicated by the arrow 5 of Fig. 1.

Fig. 6 shows, on a larger scale and in vertical section, an alternative form which may be superior in some respects to that illustrated in the preceding figures.

Fig. 7 is a bottom plan view and Fig. 8 is a side view of the last mentioned form; and Fig. 9 is a horizontal section on the line 9—9 of Fig. 6.

Referring to the details of that specific embodiment of our invention chosen for purposes of illustration (Figs. 2 and 4 being drawn upon a slightly enlarged scale), 70 11 and 12 may be respectively the upper and lower sections of a hollow and sectional drill body, these sections being shown as connected by a pin 13 and a box 14, which may be of 75 usual character, facilitating the connection and separation thereof at will; and the upper end of the upper section 11 may be provided at 15 with an interior thread adapted to receive the threaded end of a section of drill 80 pipe 16, or the like.

The lower end of the lower section 12 may be provided with a hollow neck 17, shown as carrying, in substantial alignment, a core barrel 18, having a threaded connection therewith at 19, and shown as carrying also, in a reduced portion thereof, a tubular cutter 20, externally threaded at 21 and provided with shoulders 22, adapted to contact with the lower end of the neck 17. This cutter may, however, be integral with neck 17.

The interior of the annular cutter 20 may be, and preferably is, of slightly less diameter than the interior of either the neck 17 or the core barrel 18, in order to avoid frictional contact upon an upstanding core, as the same enters and rises relatively to the mentioned parts; and the teeth of the cutter 20 may advantageously be inclined, as best shown in Fig. 2, in such manner that the cuttings formed thereby may be removed from contact with the mentioned core and forced outwardly toward the path of a pair of rotatable cutting discs 23, also supported from said neck.

Although the discs 23, or their equivalent, may be of any usual or preferred character, I have shown the same as provided with substantially flat inner faces and with substantially conical outer faces, and as extending 105 110

downwardly to substantially the same horizontal lever as, or to a lower level than the teeth of the annular cutter 20. We may mount the discs 23, or their equivalent, in any preferred manner, but we have shown the same as rotatable on and retained by nuts 24, these nuts being interiorly threaded for engagement with exterior threads upon integral studs or projections 25, extending from the neck 17, near the lower end thereof; and each of the nuts 24, these being cup shaped in general form, is preferably provided not only with an annular projecting shoulder 26, adapted to contact with the outer surface of a disc 23 or with an annular depression 27 therein, but also with an element, as a screw 28, constituting removable means for preventing accidental unscrewing and disengagement thereof. Obviously, the threads within the nuts 24, (which may be characterized as cap nuts serving also as bearings, these nuts being accordingly best formed of a comparatively hard material) should be of such direction that the rotation of the mentioned discs thereon during the cutting operation of our drill may tend rather to tighten than to loosen said nuts. It is an advantage of these nuts that they serve as readily replaceable bearings; and the described construction is such as to permit the countersinking of said nuts, to any desired degree, without corresponding loss of bearing surface.

The upper end of the core barrel 18, or its equivalent, may be provided with a valve of any preferred type, to prevent the downward entrance of a circulating mud or other fluid therethrough; and we have shown the barrel 18 as surmounted by a fitting 37 having threaded engagement therewith at 38 and serving as a cage for a ball 29. The upper surface, or any suitable surface of the fitting 37 may be apertured, as at 30, so as to permit an escape of air or other fluid initially present within the barrel 18; and the fitting 18 may also be provided with an interior annular ring or projection 31, cooperating in the retention of a seat 32 upon which the ball 29 would normally rest.

In order to permit a free circulation of mud or water, or the like, to facilitate the operation of the described cutting elements, and to remove the cuttings formed thereby, the respective sections 11 and 12 of the body or outer barrel of my drill may be respectively provided, as at 33, 33', with a central longitudinal bore or bores of sufficient diameter to permit a free downward movement of any desired fluid, the bore 33' being shown as connected, by lateral passages 34, with inclined delivery passages 35, which may terminate below the lower end of the lower barrel 18 in such manner as to assure a prompt removal of cuttings such as may be formed by the annular cutter 20 and the discs 23, or their equivalents.

In the alternative form shown in Fig. 6, this being an especially advantageous embodiment of my invention, it will be noticed that the discs 23' are set at a slight inclination, as by cutting or otherwise providing convergent flat surfaces at 39 and 39', which surfaces may represent a taper of, for example, $1\frac{1}{8}$ inch to the foot; and the teeth 20' may be formed integral with the neck 17' and may be permitted initially to project to a somewhat lower level than said discs. The convergent flat surfaces 39 and 39' may, if desired, actually encroach upon the thickness of the metal at the bases of the adjacent teeth, in order to enable the relatively moving parts referred to to co-operate effectively, without leaving any intervening ring of uncut rock; and the bases of the teeth may be appreciably thicker than the tops thereof, whether or not the respective edges of said teeth are relatively inclined in the advantageous manner shown. In this form of my invention we have also shown the bearing nuts 24' as provided with a simple and effective pin-and-slot means for preventing undesired relative rotation of these parts, this means tending to obviate all necessity for giving the screw 28' an eccentric position.

Not only the bearing nuts above mentioned but the cutting and bearing portions of the discs described, and optionally also the teeth by which the core is cut, may be formed of a special steel or steels, or hardened suitably to the exacting requirements of the indicated uses.

Although we have herein described two alternative embodiments of our invention, it will be understood that various features thereof might be independently employed, and that also various modifications might be made, by those skilled in the art to which this case relates, without the slightest departure from the spirit and scope of our invention, as the same is indicated above and in the following claims.

We claim as our invention:

1. A disc drill bit comprising a hollow body having a hollow neck to the upper end of which a core barrel is secured and to the lower end of which a tubular cutter is secured, said neck being integral with threaded studs which carry threaded bearing nuts for separate discs.

2. A drill bit comprising: a body member downwardly provided with a tubular neck, upwardly provided with external means for its reception by a drill string, and upwardly provided with internal means for receiving a core barrel; a tubular cutter downwardly mounted in coaxial alignment on said neck member; laterally projecting studs downwardly formed on said neck member; and rotatable cutting discs mounted on said projecting studs.

3. A drill bit comprising: a body member

downwardly provided with a tubular neck, 10
upwardly provided with external means for
its reception by a drill string, and upwardly
provided with internal means for receiving
5 a core barrel; a tubular cutter downwardly
mounted in coaxial alignment on said neck
member; laterally projecting studs down-
wardly formed on said neck member; and
rotatable cutting discs mounted on said pro-

jecting studs, said neck forming an annular
shoulder externally on said body, and said
shoulder having fluid circulating passages
therethrough.

In testimony whereof, we have hereunto
set our hands at Los Angeles, California, this 15
8th day of November, 1924.

JOHN T. PHIPPS.
HERMAN C. SMITH.
